Primary Examiner—Jeffrey Asch**Attorney, Agent, or Firm**—Merchant, Gould, Smith, Edell, Welter & Schmidt, P.A.**[57] CLAIM**

The ornamental design for a base unit for a wireless telephone, as shown.

DESCRIPTION

FIG. 1 is a perspective view taken from above the base unit for a wireless telephone showing our new design;
 FIG. 2 is a front elevational view of the base unit;
 FIG. 3 is a back elevational view of the base unit;
 FIG. 4 is a side elevational view of the base unit;
 FIG. 5 is a side elevational view of the other side of the base unit;
 FIG. 6 is a top plan view of the base unit; and,
 FIG. 7 is a bottom view of the base unit.
